UNITED STATES PATENT OFFICE.

WILLIAM C. FARNUM, OF FITCHBURG, MASSACHUSETTS.

LIFTING JACK.

Application filed October 20, 1921. Serial No. 509,098.

To all whom it may concern:

Be it known that I, WILLIAM C. FARNUM, a citizen of the United States, residing at Fitchburg, in the county of Worcester and State of Massachusetts, have invented a new and useful Lifting Jack, of which the following is a specification.

This invention relates to a lifting jack of the type in which a screw is employed as the lifting element.

It is the general object of my invention to improve and simplify the construction of such lifting jacks, rendering them more efficient in operation and less expensive in manufacture.

With this general object in view, important features of my invention relate to an improved and simplified casing construction, particularly adapted to receive and retain a considerable quantity of lubricant; to a novel disposition of the different parts of the worm drive, permitting a worm thread to mesh satisfactorily with a spur gear; to an improved construction of lifting nut co-operating with finished projections within the post of the jack to insure smooth and easy motion of the parts; and to a novel detachable step or cap for the upper end of the tubular lifting member.

My invention also includes an improved auxiliary hook or load engaging member for use with loads which must be engaged near the base of the jack.

My invention further relates to arrangements and combinations of parts which will be hereinafter described and more particularly pointed out in the appended claims.

A preferred form of my invention is shown in the drawings, in which—

Fig. 1 is a sectional elevation of my improved jack;

Fig. 2 is a sectional plan view taken along the line 2—2 in Fig. 1;

Fig. 3 is a plan view of the step or cap;

Fig. 4 is a front elevation of the lower portion of the jack partially in section;

Fig. 5 is a side elevation of the base of the jack; and

Figs. 6 and 7 are a plan view and side elevation of the auxiliary load engaging member or hook.

Referring to the drawings, my improved jack comprises a base 10 having an upwardly extending flange or projection 11 within which is threaded the lower end of a post 12. A tubular lifting member 13 is

slidable in bearings in the post 12 and is seated at its lower end in the recessed upward extension 14 of a lifting nut 15. The nut 15 and extension 14 are provided with axially extending grooves 16 adapted to receive ribs 17 (Fig. 2) formed on the inner surface of the post.

The sides of the ribs 17 and the sides of the grooves are preferably formed as finished surfaces equally and accurately spaced angularly, so that the nut will engage all of the ribs in every position, thus avoiding any tendency to bend the lifting screw or to otherwise throw the parts out of alignment. The ribs 17 may be conveniently finished by the use of a tool having cutting edges accurately spaced and simultaneously engaging each of the ribs, such a tool being conveniently operated in an ordinary shaping machine.

The nut 15 is actuated by a lifting screw 18, preferably of relatively steep pitch and shown herein as having a triple thread. A spur gear 19 is threaded to the lower end of the screw 18 and may be secured against displacement by the use of a cross pin 20, extending through a hub 21 on the gear 19 and also through the end of the lifting screw 18.

A ball race 22 is seated in the base 10 and a plurality of balls 23 rest thereon and form an anti-friction thrust bearing for the gear 19. A shoulder on the lower end of the post 12 prevents upward displacement of the gear.

A worm 24 (Fig. 4) is mounted in a bearing 25 in the base 10 with its axis forming an oblique angle with the axis of the screw 18 and gear 19. The worm is provided with a suitable ball or thrust bearing 26 at its lower end and is secured in position by a locking pin 27. A suitable operating device or handle 28 may be detachably secured to the upper end of the worm shaft, through which the operator may apply power to turn the worm shown herein as having a double thread.

The worm bearing is placed at such an angle that the portions of the worm threads adjacent the gear 19 are disposed substantially vertically, and the threads are so formed that they operatively engage the teeth of the spur gear 19. This construction is of importance, as it not only avoids the use of an expensive worm wheel but it also permits considerable axial variation

in the position of the gear 19, without affecting the satisfactory operation of the mechanism.

5 A step or cap 30 is provided at the upper end of the tubular member 13, said cap having a projection 31 fitting within the member 13 and having a recess 32 extending transversely of the projection. A ball 33 and spring 34 are mounted in the recess 32 and the member 13 is provided with an internal semi-circular groove 35 adapted to receive the ball as it is pressed outward by the spring 34.

10 Displacement of the cap is thus prevented while at the same time the cap may rotate freely in the member 13. A small opening 36 in the member 13 permits the insertion of a pin or wire to press back the ball 33 when the parts are to be separated.

15 20 Annular recesses 37 are provided near the upper end of the post 12 to receive packings 38 which closely engage the member 13 and prevent escape of lubricant from the post or casing. This construction permits the whole interior of the post 12 to be filled with oil or other suitable lubricant and effectively excludes dirt therefrom.

25 30 In Figs. 6 and 7 I have shown an auxiliary load engaging device or hook comprising a semi-cylinder sleeve-like body portion 40 having a head 41 at its upper end and a projection or hook 42 at its lower end. The head 41 is provided with a transversely extending flange 43 adapted to be seated in a recess 44 in the step or cap 30. This auxiliary device is extremely useful where it is necessary to lift a load which can only be engaged near the base of the 35 40 jack.

45 Having thus described my invention it will be evident that changes and modifications can be made therein by those skilled in the art within the spirit and scope of my invention as set forth in the claims, and I do not wish to be otherwise limited to

the details herein disclosed but what I claim is:—

1. A lifting jack having, in combination, a substantially cylindrical base with its upwardly extending portion internally threaded, a cylindrical post threaded in said portion and extending upwardly therefrom, a tubular member slideable but non-rotatable in said post, a lifting screw having a threaded connection to said member, a spur gear fixed to said screw and positioned between portions of said base and post which limit axial movement thereof, and an actuating worm for said gear mounted in a bearing in the side of said base disposed at an oblique angle to the axis of the screw, said worm accurately engaging said gear in any vertical relation of said parts. 55

2. In a lifting jack, a non-rotatable tubular load supporting member, means to force said member upward, a cap for said member, and a yielding locking device detachably securing said cap to said member, said means permitting free relative angular 60 movement between said cap and member. 70

3. In a lifting jack, a tubular member, a cap for said member, and means to detachably secure said cap in said member, said member having an internal groove near its upper end and said cap having a projection fitting within said member and having a locking ball yieldingly mounted in a transverse opening in said projection in position to be retained in said groove, thereby locking the parts together. 75

4. A lifting jack comprising a post, a lifting screw, a cap movable thereby, and a load-engaging member having a semi-cylindrical sleeve-like body portion, an upper portion engaging said cap, and a lower hook-like projection to engage the load, the body portion closely fitting the exterior of said post. 85

5. In testimony whereof I have hereunto affixed my signature.

WILLIAM C. FARNUM.
